UNITED STATES PATENT OFFICE

MICHAEL R. McDANAL, OF DENVER, COLORADO

DESIGN FOR A SPECTACLE FRAME

Application filed January 27, 1933. Serial No. 47,013. Term of patent 14 years.

To all whom it may concern:

Be it known that I, MICHAEL R. McDANAL, a citizen of the United States, residing in the city and county of Denver, State of Colorado, have invented a new, original, and ornamental Design for a Spectacle Frame, of which the following is a specification, reference being had to the accompanying drawing, forming part thereof.

Fig. 1 is a front elevation of a spectacle frame showing my new design.

Fig. 2 is a top view of Fig. 1.

Fig. 3 is a greatly enlarged detail view of the front of the temple bar mounting and a fragment of the adjacent rim.

Fig. 4 is a greatly enlarged detail view of the front of the nose bridge mounting and fragments of the adjacent rim and the nose bridge.

I claim:

The ornamental design for a spectacle

MICHAEL R. McDANAL.
